United States Patent Office

Des. 227,641
Patented July 10, 1973

227,641

CREAMER

John W. Downey, Warren, Pa., assignor to Whirley
Industries, Inc., Warren, Pa.

Filed May 13, 1971, Ser. No. 143,296

Term of patent 14 years

Int. Cl. D7—01

U.S. Cl. D7—60

Fig. 1

FIG. 2

FIG. 4

FIG. 3

FIG. 1 is a front perspective view of a creamer showing my new design;

FIG. 2 is a rear perspective view thereof;

FIG. 3 is a front perspective view thereof;

FIG. 4 is a side perspective view thereof. The bottom of the creamer is plain.

I claim:

The ornamental design for a creamer, as shown and described.
